(57) CLAIM

The ornamental design for a snow globe soap bottle, as shown and described.

DESCRIPTION

FIG. 1 is a front side elevation view of a snow globe soap bottle with a Christmas tree embodying our new design in which the particles are settled; and,

FIG. 2 is a front side elevation view thereof in which the particles are suspended some time after agitation, in which the particles partially obscure the Christmas tree.

There are no top, bottom, left, right, or rear elevational views, as the ornamental features of the design are either not claimed or not seen from those perspectives.
